Daniel A. Klimkiewicz, Rutherford, N.J., assignor of one-half interest to Ronald A. Darby, Hawthorne, N.J.

Filed Sept. 23, 1965, Ser. No. 87,128

Term of patent 14 years

(Cl. D12—2)

FIG. 1

The right side elevational view not shown herein is a mere image of the left side elevational view shown in FIGURE 3.

The fragmentary broken line portion represents a partial showing of a dog collar for illustrative purposes only.

I claim:

The ornamental design for a dog collar ornament or similar article, as shown and described.
